[57] CLAIM

The ornamental design for an insulated beverage and food cooler bag, substantially as shown and described.

DESCRIPTION

FIG. 1 is a front view of an insulated beverage and food cooler bag.

FIG. 2 is a right side view thereof.

FIG. 3 is a rear view thereof.

FIG. 4 is a left side view thereof.

FIG. 5 is a top view thereof.

FIG. 6 is a bottom view thereof; and,

FIG. 7 is a front view of an alternate embodiment; the right side, left side, rear, top and bottom views being substantially the same as the embodiment of FIGS. 1 through 6.
